UNITED STATES PATENT OFFICE.

JOSEPH HOSL, OF YANKTON, SOUTH DAKOTA.

PLOW.

1,099,300.

Specification of Letters Patent.

Patented June 9, 1914.

Application filed October 16, 1913. Serial No. 795,470.

To all whom it may concern:

Be it known that I, JOSEPH HOSL, a subject of the Emperor of Germany, residing at Yankton, in the county of Yankton and State of South Dakota, have invented certain new and useful Improvements in Plows, of which the following is a specification.

This invention relates to plows which have a reversible share to permit plowing on a side-hill, returning in the last-made furrow and throwing down-hill each way.

The object of the present invention is to provide a novel and improved form of reversible share and a support therefor by which reversal of the share is readily effected.

Other objects and advantages of the invention will be pointed out in the detailed description appearing hereinafter.

In order that the invention may be better understood, reference is had to the accompanying drawings in which—

Figure 1 is a side elevation of the plow and Fig. 2 is a rear end view thereof; Fig. 25 3 is a plan view, and Fig. 4 is an elevation of the rear end of the plow at the land side thereof.

Referring specifically to the drawings, 10 denotes the beam of the plow, the same being provided with handles 11 at its rear end and its front end being equipped with an adjustable clevis 12 for attachment of the draft animals.

At 13 is indicated two vertically spaced landsides, each having a rearward extension 14. The landsides are connected by a web 15 and from one side of the same extends a double mold-board 16. From the back of the mold-board project, rearward, 40 shoes 16^a located, respectively, on the same level as the extensions 14. The mold-board and the parts associated therewith are rotatable in a horizontal plane so that the plow may throw to the left or to the right.

On the bottom of the beam 10 are ears 17 to which is hinged, as indicated at 18, a hanger 19 which extends downward and has its lower extremity bifurcated, as indicated at 20. A lug or knuckle 21 on the land side 50 of the web 15, midway between the landsides 13, fits between the bifurcations 20 and a pin 22 passing through said parts provides the pivotal support of the mold-board 16 and its associate parts. The 55 hanger 19 is hinged at its rear end, and at its forward end it has an upstanding stem

23 which passes loosely through a vertical aperture 24 in the beam 10 and rises a short distance therefrom.

To a suitable support 25 on top of the beam 10 is fulcrumed, as indicated at 26, one end of a hand-lever 27 which extends rearward and terminates between the handles 11. Intermediate its ends, the hand-lever carries a vertical stem 28 which passes loosely through an aperture in the beam 10, and has at its lower end, below said beam, a cross-bar 29 provided with a pair of laterally spaced bottom notches 30. Between the cross-bar 29 and the bottom of the beam 10, a spring 31 is coiled around the stem 28, which spring tends to urge the stem, and the cross-bar carried thereby, downward. These parts form a latch for locking the mold-board 16 and its associate parts 75 in adjusted position. The notches 30 are on opposite sides of the beam 10, and are engageable by either one of the parts 14 for the purpose stated. Figs. 1 and 2 of the drawings shows the mold-board set to 80 throw to the left of the beam 10, hence the part 14, which is now at the top of the mold-board, engages the left notch. When the mold-board is reversed to throw to the right, the part 14, which is now at the top, seats 85 in the right notch. It will therefore be evident that the mold-board and its associate parts are securely locked in either position, and to unlock the same it is necessary only to lift the latch, which is done by swinging 90 the hand-lever 27 upward. The ends of the cross-bar 29 are beveled so that the latch may snap into holding position.

The hinge connection 18 permits the parts carried by the hanger 19 to be lowered to 95 regulate the depth of the plow, this adjustment being effected by means of a hand-lever 32 carried by the beam 10 and connected by a coiled spring 33 to one end of a lever 34 pivoted at its other end to the support 25, 100 and pivotally connected at 35, intermediate its ends, to the upper end of the stem 23. Upon swinging the hand-lever 32 forward, the hanger 19 tilts downward and forward, thereby tilting the plow point correspondingly. The resilient connection 33 allows the plow to yield to clear obstructions. The beam 10 also carries a rolling colter 36 operating in the ordinary manner.

By the structure herein described a double 110 and reversible plow is had, the ground-engaging parts being duplicated on diamet-

rically opposite sides of the pivot 22, so that either part may be put in position for use. It is therefore possible to reverse the plow at the end of the furrow and return along-
5 side the same. The web 15 and the top landside 13 bear against one side of the hanger 19, which, with the latch, firmly holds the plow in adjusted position, the hanger effectually serving to sustain the side
10 thrust.

I claim:

1. A plow comprising a beam, a hanger depending from the beam, vertically spaced landsides, a web connecting the landsides, a
15 double mold-board extending from the landsides and the web, and a horizontal pivotal connection between the hanger and the web midway between the landsides, to permit reversal of the landsides and the mold-board, the web and uppermost landside bearing against one side of the hanger.
2. A plow comprising a beam, a hanger pivoted to the beam to tilt forward and downward, and a reversible mold-board and
25 associate parts carried by the hanger.
3. A plow comprising a beam, a hanger pivoted to the beam to tilt forward and downward, a reversible mold-board and associate parts carried by the hanger, a verti-

cal stem rising from the hanger, the beam 30 having an aperture through which said stem passes, a lever pivoted to the upper end of the stem, a hand-lever carried by the beam, and a connection between said levers.

4. A plow comprising a beam, a hanger 35 pivoted to the beam to tilt forward and downward, a reversible mold-board and associate parts carried by the hanger, a vertical stem rising from the hanger, the beam having an aperture through which said stem 40 passes, a lever pivoted to the upper end of the stem, a hand-lever carried by the beam, and a resilient connection between said levers.

5. A plow comprising a beam, a hanger carried by the beam, and a double mold-board and associate parts pivoted to the bottom of the hanger to swing in a vertical plane and come against either side of the hanger, said mold-board and associate parts being duplicated on diametrically opposite sides of the pivot.

In testimony whereof I affix my signature in presence of two witnesses.

JOSEPH HOSL.
